Job's Daughters, Chicago, Ill.

Application July 28, 1943, Serial No. 110,777

Term of patent 14 years

To all whom it may concern:

Be it known that I, Warde C. Cookman, a citizen of the United States, residing at Wilmette, in the county of Cook and State of Illinois, have invented a new, original, and ornamental Design for an Emblem Pin or Similar Article, of which the following is a specification, reference being had to the accompanying drawing, forming part thereof.

In the drawing:

Fig. 2 is a side elevation thereof; and

Fig. 3 is a section on line 3—3 of Figure 1.

The essential features of my design reside in the formation in bas-relief of the three figures in the central portion of the triangularly shaped body of the emblem, said central portion being depressed so that said figures are positioned below the plane of the marginal portion of the design, as best shown in Fig. 3, the edges of the emblem being bevelled and the bevelled surfaces at the two sides being provided with ornamental filigree, as shown.

I claim:

The ornamental design for an emblem pin or similar article, substantially as shown and described.

WARDE C. COOKMAN.
